PAGE MARKING CLIP

Mary C. Saksa, St. Louis, Mo.

Application February 6, 1952, Serial No. 18,405

Term of patent 3½ years

(Cl. D6—2)

To all whom it may concern:

Be it known that I, Mary C. Saksa, a citizen of the United States, residing in the city of St. Louis, State of Missouri, have invented a new, original, and ornamental Design for a Page Marking Clip, of which the following is a specification, reference being made to the accompanying drawing forming a part thereof, in which

The figure is an enlarged perspective view of a page marking clip, showing my new design, the opposite side presenting substantially the same appearance as the side shown.

I claim:

The ornamental design for a page marking clip, substantially as shown and described.

MARY C. SAKSA.
